M. J. HORSWILL

ELECTRIC WATER HEATER

Filed March 5, 1923

Fig. 2.

Fig. 1.

Inventor:

MILTON J. HORSWILL.

BY
Harry S. Schneider
ATTORNEY.

UNITED STATES PATENT OFFICE.

MILTON J. HORSWILL, OF OAKLAND, CALIFORNIA, ASSIGNOR TO ANNA B. DONAHOO,
OF ALAMEDA, CALIFORNIA.

ELECTRIC WATER HEATER.

Application filed March 5, 1923, Serial No. 622,810.

To all whom it may concern:

Be it known that I, MILTON J. Horswill, a citizen of the United States, residing at Oakland, in the county of Alameda and State of California, have invented certain new and useful Improvements in Electric Water Heaters, of which the following is a specification.

My invention is an improved electric water heater.

One of the objects of my invention is to provide a heater which is detachably mounted upon the faucet, and may be readily attached or removed therefrom.

Other objects of my invention are to provide a heater which is simple in construction, efficient in operation, and inexpensive to manufacture.

In the drawing in which my invention is illustrated:

Figure 1 is a longitudinal sectional view of my electric heater.

Figure 2 is a sectional view taken on the line 2—2 of Fig. 1.

Referring more particularly to the drawing, the numeral 1 indicates a housing which is closed at the ends by caps 2 and 3 which are formed of an insulating material. Spaced between the caps 2 and 3 is an outer conducting core 4 and an inner conducting core 5, which are preferably formed of carbon. The core 5 is positioned within the core 4 and is spaced therefrom to form an annular water passage 6. The cap 3 has an annular intake chamber 7 which communicates with the passage 6, and the cap 2 has an annular outlet chamber 8 also communicating with said passage. A terminal 9 extends through the cap 2 and is secured to the core 4, and a terminal 10 extends through both caps 2 and 3 and through the core 5, thus binding the said caps and core together.

An outlet pipe 11 extends into the annular chamber 8 through the cap 2 and an intake pipe 12 extends into the chamber 7 through the cap 3. A faucet coupling sleeve 13 is adapted to fit over a faucet 14 and is preferably molded of some yieldable material so that it will grip the faucet and yet may be easily removed therefrom.

The water enters my heater through the pipe 12 and chamber 7. It rises through

the annular passage 6 where it forms contact between the cores 4 and 5 and is heated. After it is heated the water flows out of the pipe 11.

Having described my invention, I claim:

1. An electric heater comprising a conducting core, a second conducting core, said second core being spaced from said first core to form an annular water passage through which the water is adapted to flow, a cap at both ends of said cores, said caps having annular chambers therein communicating with said water passage, an inlet pipe extending into one of said annular chambers, and an outlet pipe extending into the other annular chamber, an electric terminal connected to one core and a second electric terminal connected to the other core, said second terminal being a post extending through one of the cores and both caps.

2. An electric heater comprising a conducting core, a second conducting core, said second core being spaced from said first core to form an annular water passage through which the water is adapted to flow, a cap at both ends of said cores, said caps having annular chambers therein communicating with said water passage, an inlet pipe extending into one of said annular chambers, and an outlet pipe extending into the other annular chamber, and a faucet coupling sleeve secured to said inlet pipe, electric terminals connected to the cores, one of said terminals being a post extending through the inner core and both of the caps.

3. An electric heater comprising a circular core, a hollow tubular core surrounding and spaced from said first core to form an annular water passage, through which the water is adapted to flow, a cap at both ends of said cores, each cap having an annular chamber communicating with said water passage, a terminal passing through both caps and a bore extending through the inner core and having means thereon to hold said caps on said cores, an inlet pipe extending into one of said annular chambers, an outlet pipe extending into the other annular chamber and a faucet coupling sleeve secured to said inlet pipe.

In testimony whereof I affix my signature.

MILTON J. HORSWILL,
